Joseph Crompton INVENTOR.

UNITED STATES PATENT OFFICE.

JOSEPH CROMPTON, OF CHICAGO, ILLINOIS, ASSIGNOR TO THE MEYERCORD COMPANY, OF CHICAGO, ILLINOIS.

DESIGN FOR AN ARTICLE OF MANUFACTURE.

48,486.

Specification for Design.

Patented Feb. 1, 1916.

Application filed November 1, 1915. Serial No. 59,156. Term of patent 3½ years.

To all whom it may concern:

Be it known that I, JOSEPH CROMPTON, a citizen of the United States, residing at Chicago, in the county of Cook, State of Illinois, have invented a new, original, and ornamental Design for an Article of Manufacture, of which the following is a specification, reference being had to the accompanying drawing, forming a part thereof.

The figure is a plan view of my design to be applied to an article of manufacture.

I claim—

The ornamental design for an article of manufacture as shown.

JOSEPH CROMPTON.

Witnesses:

C. JAROS,

F. P. VEETH.
